UNITED STATES PATENT OFFICE

118,571

DESIGN FOR A LAMP

John A. Schachte, Brooklyn, N. Y.

Application June 22, 1939, Serial No. 85,622

Term of patent 3½ years

To all whom it may concern:

Be it known that I, John A. Schachte, a citizen of the United States, residing at Brooklyn, in the county of Kings and State of New York, have invented a new, original, and ornamental Design for a Lamp, of which the following is specification, reference being had to the accompanying drawing, forming part thereof.

side elevation of a lamp showing my new design.

Fig. 3 is a top plan view thereof with the members illustrated by broken lines omitted.

The dominant features of my design reside in the portions of the lamp shown in solid lines.

I claim:

The ornamental design for a lamp, as shown and described.

JOHN A. SCHACHTÉ.
